UNITED STATES PATENT OFFICE.

FRED CUSHMAN, OF SEATTLE, WASHINGTON, ASSIGNOR OF ONE-HALF TO C. J. STEPHANUS, OF SEATTLE, WASHINGTON.

ORE-SEPARATOR.

1,368,901.

Specification of Letters Patent. Patented Feb. 15, 1921.

Application filed October 7, 1916. Serial No. 124,378.

To all whom it may concern:

Be it known that I, FRED CUSHMAN, a citizen of the United States, residing at Seattle, in the county of King and State of Washington, have invented certain new and useful improvements in Ore-Separators, of which the following is a specification, reference being had to the accompanying drawings.

10 This invention relates to certain improvements in ore separators and has relation more particularly to a device of this general character especially designed and adapted for use in connection with auriferous matter 15 and is of such construction as to be readily adapted for use in placer and drift mining or for free milling quartz in connection with a pulverizing machine; and it is an object of the invention to provide a device of this 20 general character having novel and improved means whereby all of the values in the sand, gravel or quartz regardless of the flour or float gold, will be reclaimed.

The invention also has for an object to 25 provide a device of this general character wherein a vibratory concentrating unit is employed and wherein movement is mechanically imparted thereto in one direction and automatically imparted in the opposite 30 direction.

The invention also has for an object to provide a device of this general character including a vibratory concentrating unit and a sluice box operatively engaged there- 35 with and discharging thereto, said sluice box being vibrated under the influence of the movements of the concentrating unit.

A still further object of the invention is to provide a device of this general character 40 including a concentrating unit having co-acting therewith novel and improved means for collecting the flour or float gold and wherein said means includes an endless collecting table caused to travel intermittently 45 under the influence of the movements or vibrations of the concentrating unit.

The invention consists in the details of construction and in the combination and arrangement of the several parts of my im- 50 proved ore separator whereby certain im- portant advantages are attained and the de- vice is rendered simpler, less expensive and otherwise more convenient and advantageous for use, all as will be hereinafter more fully 55 set forth.

The novel features of the invention will hereinafter be definitely claimed.

In order that my invention may be the better understood, I will now proceed to de- 60 scribe the same with reference to the accom- panying drawings, wherein—

Figure 1 is a view in side elevation illustrating an ore separator constructed in accordance with an embodiment of my invention; 65

Fig. 2 is an enlarged fragmentary view in vertical section taken longitudinally of the concentrator box as herein included;

Fig. 3 is a view in top plan of the concentrator box as herein employed, the coact- 70 ing bumper being shown in section;

Fig. 4 is a fragmentary view in side elevation of the upper end portion of the concentrator box; and

Fig. 5 is a fragmentary view in top plan 75 of the lower end portion of the lower sluice box as herein disclosed.

As disclosed in the accompanying drawings, F denotes a frame of suitable construc- 80 tion and configuration and which is pro- vided with the depending hangers 1 capable of longitudinal adjustment through the medium of the nuts 2 in threaded engagement therewith.

Engaged with the hangers 1 are the flexi- 85 ble members 3 which serve to support the sluice boxes 4 and 5, the adjacent ends of said sluice boxes being pivotally connected one with the other as indicated at 6, and said sluice boxes 4 and 5 are disposed on a predetermined incline. It will be perceived that the support afforded by the flexible members 3 will permit said boxes to have a vibratory movement and that the endwise adjustment of the hangers 1 will permit a 90 varying of the angles of inclinations of said boxes as the requirements of practice may determine.

The upper sluice box 4 discharges into the lower sluice box 5 and the lower end of 100 the box 5 is provided with the extension or plate 7 to carry off the tailings.

The sluice boxes 4 and 5 are of any ordinary or preferred construction and the lower box 5 has positioned therebeneath and 105 carried thereby the collecting apron or hood 8 into which is discharged the concentrates passing down the box 5.

The apron or hood 8 is provided with a discharge opening 9 preferably rectangular 110

in plan and which is defined by the depending sleeve or spout 10 discharging into the concentrator box or unit 11. The box or unit 11 is disposed on a predetermined incline opposite to that of the sluice boxes 4 and 5 and is supported for vibration through the medium of the hangers 12 and the flexible members 14, said hangers 12 being also capable of endwise adjustment through the medium of the nuts 15 in order to control or vary the degree of inclination of the box 11 and which inclination is preferably one inch to the foot.

15 Rotatably supported by the frame F above the box 11 and disposed transversely of said box is a shaft 16 adapted to be driven in any desired manner and which is provided with the cam 17 coacting with the roller 18 rotatably supported by the upper 20 portion of the box 11, whereby it will be perceived that the box 11 is caused to move in one direction.

25 Operatively engaged with the upper end portion of the box 11 at opposite sides there- of are the rods 19 which are loosely disposed through the bumper 20 suitably supported by the frame F, and the outer ends of the rods 19 are provided with the abutments or shoulders 21.

30 Interposed between the bumper 20 and the abutments or shoulders 21 are the expansible members 22 herein disclosed as conventional coil springs encircling the rods 19. It will be perceived that as movement is imparted 35 to the box 11 in one direction under the influence of the cam 17, the expansible members 22 will be compressed so that when the cam 17 is disengaged from the roller 18, the box 11 will be caused to automatically move 40 in an opposite direction and with great force so that when the same contacts with the bumper 20, the box will be brought to a sudden stop with the result that the concentrates within the box 11 will be thoroughly 45 agitated. The upper end of the box 11 is provided with the buffer 23 which is positioned for direct contact with the bumper 20 so that the life of the box 11 will be prolonged.

50 The lower portion of the box 5 has secured to the sides thereof the depending arms 24 which are pivotally engaged with the sides of the box 11 adjacent the upper end thereof, whereby it will be perceived that the vibration 55 of movements of the box 11 will result in the vibration of the boxes 4 and 5 so that the auriferous material passing over said boxes 4 and 5 will be effectively agitated.

The box 11 adjacent its upper end is provided in its bottom with the transverse opening 25 in which is rotatably mounted the roller 26 over which passes the upper stretch of the endless carpet or value collecting apron 27, said carpet or apron 27 passing downwardly of the box 11 and around the

roller 28 positioned at the lower end of said box 11. The lower stretch of the carpet or apron 27 underlies the box 11 and passes over the guide roller 29 rotatably supported by and between the arms 30 depending from opposite sides of the box 11 adjacent the opening 25.

The arms 30 are adapted to guide the carpet or apron 27 into a receptacle R containing water so that the flour or floating gold collected by said carpet or apron may be thoroughly washed therefrom and so that said flour or floating gold may be reclaimed 75

The roller 28 has coacting therewith the sprocket 31 around which is disposed the sprocket chain 32 which is also directed around the idle sprocket 33 rotatably supported by a side of the box 11 adjacent the upper end thereof. The sprocket 33 is also provided with the ratchet teeth 34 with which coacts the gravity pawl 35 pivotally supported by a longitudinal bottom 36 comprised in the frame F and positioned to one side of the box 11. By this arrangement it will be perceived that as the box 11 is caused to move under the influence of the cam 17, the sprocket 33 will be intermittently rotated through the coaction between the ratchet 34 and the pawl 35 whereby it will be perceived that the carpet or apron 27 will be caused also to intermittently travel.

From the foregoing description, it is thought to be obvious that an ore separator constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

1. An ore separator comprising, in combination, a sluice box mounted for vibratory movement and disposed longitudinally on a predetermined incline, a collecting hood underlying the sluice box and provided with a discharge opening, a discharge spout depending from the hood and defining the discharge opening, a plate extending beyond the lower end of the sluice box over which the tailings are adapted to be discharged, a concentrator box positioned below the sluice box and mounted for vibratory movement, arms depending from the sides of the sluice box adjacent the lower end thereof, said arms being pivotally engaged with the adjacent end portion of the concentrator box whereby the vibratory movement of the concentrator 130

box serves to vibrate the sluice box, and means for vibrating the concentrator box.

2. An ore separator comprising, in combination, a sluice box mounted for vibratory movement and disposed longitudinally on a predetermined incline, a collecting hood underlying the sluice box and provided with a discharge opening, a discharge spout depending from the hood and defining the discharge opening, a plate extending beyond the lower end of the sluice box over which the tailings are adapted to be discharged, a concentrator box positioned below the sluice box and mounted for vibratory movement, said concentrator box being disposed longitudinally on a predetermined incline in a direction opposite to the inclination of the sluice box, the upper end portion of the concentrator box being provided with an opening, the depending spout of the collecting hood discharging within the concentrator

box at a point below the opening, arms depending from the sides of the sluice box adjacent the lower end thereof, said arms being pivotally engaged with the adjacent end portion of the concentrator box whereby the vibratory movement of the concentrator box serves to vibrate the sluice box, means for vibrating the concentrator box, a receptacle positioned below the concentrator box, an endless value collecting apron overlying the bottom of the concentrator box, passing through the opening in the concentrator box and extending within the receptacle, and means for imparting movement to the endless value collecting apron.

In testimony whereof I hereunto affix my signature in the presence of two witnesses.

FRED CUSHMAN.
